DENTAL TRAY

Kenneth E. Merrill, 8136 Juniper, Shawnee Mission, Kans.
66208, and Burton K. Cox, 6400 W. 100th, Overland
Park, Kans. 66212

Filed Mar. 29, 1973, Ser. No. 346,075

Term of patent 14 years

Int. Cl. D24—02

U.S. Cl. D24—1 R

FIG. 1 is a perspective view of a dental tray, showing our new design;

FIG. 2 is a side elevational view thereof;

FIG. 3 is an end elevational view taken from the right hand end of FIG. 1; and

FIG. 4 is an end elevational view taken from the left hand end of FIG. 1 of a dental tray.

We claim:

The ornamental design for a dental tray, as shown.
